CLAIM

The ornamental design for a combination water dispenser, purifier, and carbonator, as shown and described.

DESCRIPTION

Fig. 1.1 is a front, top, and right perspective view of a combination water dispenser, purifier, and carbonator.

Fig. 1.2 is a rear, bottom, and left perspective view of a combination water dispenser, purifier, and carbonator.

Fig. 1.3 is a front elevational view of a combination water dispenser, purifier, and carbonator.

Fig. 1.4 is a rear elevational view of a combination water dispenser, purifier, and carbonator.

Fig. 1.5 is a left side perspective view of a combination water dispenser, purifier, and carbonator.

Fig. 1.6 is a right side perspective view of a combination water dispenser, purifier, and carbonator.

Fig. 1.7 is a top perspective view of a combination water dispenser, purifier, and carbonator.

Fig. 1.8 is a bottom perspective view of a combination water dispenser, purifier, and carbonator.
